[57] **CLAIM**

The ornamental design for a solid fuel burning stove unit for use as fireplace insert or free-standing heater, as shown and described.

DESCRIPTION

FIG. 1 is a front perspective view of a solid fuel burning stove unit for use as fireplace insert or free-standing heater, showing my new design;

FIG. 2 is a front elevation view thereof, the back being plain; and

FIG. 3 is a side elevation view thereof viewed from the right of FIG. 2, the opposite side elevation being the mirror image thereof.

The screen member is shown partially broken away in FIG. 2 for clarity of disclosure.
